CLAIM

The ornamental design for an electronic copying machine, as shown and described.

DESCRIPTION

FIG. 1 is a top, front and right side perspective view of an electronic copying machine showing our new design with the platen cover and sub-control panel in the open position;

FIG. 2 is a top plan view thereof;

FIG. 3 is a left side elevational view thereof;

FIG. 4 is a front elevational view thereof;

FIG. 5 is a right side elevational view thereof;

FIG. 6 is a bottom plan view thereof;

FIG. 7 is a rear elevational view thereof; and,

FIG. 8 is an enlarged fragmentary view of the control panel in an activated condition.

FIG. 1

FIG. 2

FIG. 4

FIG. 3
